BUBBLE PIPE

Arthur E. Neumann, Wilmette, Ill.

Application August 23, 1944, Serial No. 550,689

6 Claims. (Cl. 46—6)

1

This invention relates to devices for forming bubbles from suitable solutions, commonly soap solutions, usually termed bubble pipes.

Bubble pipes are well known and extensively used. My invention is directed to a bubble pipe embodying certain features rendering it more attractive to children, and others, than the ordinary bubble pipe while also rendering it possible to blow bubbles with greater ease and accuracy than is possible with any known bubble pipe with which I am familiar. More specifically, I provide a bubble pipe embodying a wind instrument, such as a whistle, which is sounded simultaneously with the blowing of a bubble, in conjunction with means whereby the flow of air to the wind instrument and to the bubble blowing compartment of the pipe may readily be variably proportioned to attain the desired results. The pipe bowl comprises a bubble blowing compartment and a liquid container, with which the wind instrument communicates for producing a bird call effect, means being also provided for varying the pitch of the wind instrument. I also provide an improved outlet opening from the bubble blowing compartment, of a character to assure proper retention of the bubble forming solution while permitting ready separation or freeing of the formed bubble without breaking thereof, and means for shielding the film and the bubble being formed therefrom from impingement thereon of the entering air stream, so as to guard against breakage of the film or of the incompletely formed bubble from that cause, as well as means for regulating the flow of air through the stem of the pipe into the bubble blowing compartment. Further objects and advantages of my invention will appear from the detail description.

In the drawings:

Figure 1 is a side view of a bubble pipe embodying my invention;

Figure 2 is a plan view of the bubble pipe of Figure 1;

Figure 3 is a sectional view taken substantially on line 3—3 of Figure 2;

Figure 4 is an outer end view of the stem of the pipe on an enlarged scale; and

Figure 5 is a sectional view, taken substantially on line 5—5 of Figure 3, on an enlarged scale.

I have illustrated my invention, by way of example, as embodied in a pipe comprising a cylindrical bowl 6 separated by horizontal partition 7 into an upper compartment 8 and a lower compartment 9. The upper compartment 8 is closed at its top by a wall 10 having therein a restricted opening 11 to atmosphere, and the lower compartment is provided with a bottom wall 12 having a central depending annular lip 13 defining an outlet opening 14, the lower edge of the lip 13 being rounded at 15, for a purpose which will appear presently.

A tubular stem 16 extends outward from bowl 6, this stem defining two separate passages dis-

2

posed in superposed relation, upper passage 17 being constructed in the form of a wind instrument approximating an organ tube so as to provide a whistle, shown in Figure 3, the upper portion of this passage tapering upward and outward, and lower passage 18, flares downward and inward towards the bowl 6. The upper portion of stem 16 extends into compartment 8 so that passage 17 opens into this compartment adjacent the bottom thereof, and passage 18 opens into compartment 9 adjacent the top thereof, with partition 19 separating the passages 17 and 18 extending from partition 7. Bowl 6 is further provided with a baffle 20, extending inward therefrom from the lower wall of stem 16 and disposed between the lower end of passage 18 and the outlet opening 14, this baffle serving to deflect toward partition 7 the air stream flowing through passage 18 and to disperse the air more or less uniformly 20 within compartment 9, preventing a direct discharge of air from passage 18 into or through the outlet opening 14, the advantage of which will be explained presently. Conveniently, the step 16 is formed integrally with bowl 6, the pipe, including the stem, being formed, by molding in a known manner, from a synthetic resin or plastic, or other suitable material, which possesses sufficient rigidity to be self-sustaining sufficiently to retain the form into which it is molded while being 30 readily flexible, particularly at relatively thin areas thereof. The upper end portion 21 of the lower wall or portion of stem 16 is relatively thin and inclined upward and outward at a slight angle to the main portion of that wall, to provide a restricted opening 22 at the outer end of passage 18, the thin portion 21 of the wall being readily flexible so that by being bent inward it may function to constrict the upper portion of passage 18. The upper portion 23 of the upper or top wall 40 of stem 16 is inclined outward toward partition 19, providing a restricted opening 24 at the upper end of passage 17. The inclined portions 21 and 23 of the lower and upper walls of the stem, together with the side portions of the walls thereof, provide a mouthpiece at the upper or outer end 45 of the stem having therein the two openings 22 and 24 for blowing simultaneously through both of the passages.

In using the bubble pipe, the upper compartment 8 of bowl 6 is filled with water or other suitable liquid to about the height shown in Figure 3, so that the lower end of passage 17 is disposed at an appreciable distance below the surface of the liquid. In order to blow a bubble, the depending lip 13 is dipped into a suitable bubble forming solution, such as a soap solution, which solution is retained in the opening 14 in the form of a film extending thereacross. By blowing through the stem 16, air is caused to flow through the passages 17 and 18 thereof, the air from the latter passage entering the compartment 9 and being deflected upward therein by the baffle 20. This air distends

the film extending across the opening 14 into bubble form, and when this film has been blown into a bubble of the desired size, the resultant bubble may readily be detached from lip 13 by imparting a sharp movement or jerk to the pipe, the rounded edge 15 at the lower end of lip 13 facilitating detachment of the bubble without risk of breakage thereof. The inward flare of passage 18 is of advantage in that it reduces the velocity of air flowing through this passage, which in conjunction with the baffle 20, disposed to prevent direct impingement of the entering air stream upon the film extending across opening 14 or the partially formed bubble, reduces likelihood of breakage of the film or the partially formed bubble by blowing too violently through the passage 18. When the user of the pipe blows through the passage 16 of stem 16, he also blows through the passage 17 and causes sounding of the whistle formed by this passage, the water or other liquid within the compartment 8 being caused to bubble or burble by the air discharged into that compartment from the lower end of passage 17, so as to impart to the sound produced a trilling or bird call effect. This bubbling or burbling and the trilling effect produced thereby may be stopped by closing the restricted opening 11. To a certain extent, the pitch of the sound produced by the wind instrument may also be varied by closing opening 11, as the pressure then developed in passage 17 will force some of the water therefrom into bowl 6 thereby lengthening passage 17 with a consequent variation in the pitch of the sound produced. By displacing the relatively thin portion 21 of the stem, so as to contract the upper portion of passage 18, the flow of air through the passages 17 and 18 may be variably proportioned so as to increase or diminish the intensity of the sound produced by the whistle. In addition, the readily flexible portion 21 of the stem provides convenient means for controlling the air flow through passage 18, whereby the air flow into compartment 9 may be regulated in a manner to facilitate blowing of bubbles with greater accuracy and less danger of breakage than is possible where such control means is not provided.

While I preferably form the stem of the pipe integrally with the bowl, as shown, that is not essential to the broader concept of my invention, which comprehends a pipe having a bowl and a stem associated in any manner suitable for effecting the results attained by my invention. The stem 16 is shown as of substantially elliptical cross section but it may be of any other suitable shape desired. It will be understood that changes in construction and arrangement of parts of my invention may be resorted to without departing from the field of scope thereof, and I intend to include all such variations, as fall within the scope of the appended claims, in this application in which the preferred form only of my invention has been disclosed.

I claim:

1. In a bubble pipe, a readily flexible bowl formed of a plastic and comprising two separate compartments, one adapted for reception of a liquid and having restricted communication with atmosphere and the other compartment having a restricted outlet opening adapted for reception of a bubble forming solution, and a tubular stem comprising two separate passages, one constructed to provide a whistle opening into said one compartment adjacent the bottom thereof and the other opening into said other compartment.

2. In a bubble pipe, a readily flexible bowl

formed of a plastic and comprising two separate superposed compartments, the upper adapted for reception of a liquid and the lower having a restricted outlet opening adapted for reception of a bubble forming solution, and a tubular stem comprising two separate superposed passages, the upper constructed to provide a whistle opening into said upper compartment adjacent the bottom thereof and the lower opening into said lower compartment.

3. In a bubble pipe, a bowl comprising a compartment closed at its upper end and having an outlet opening at its lower end adapted for reception of a bubble forming solution, a stem defining a passage opening into said compartment adjacent the upper end thereof, and a baffle within said compartment spaced from the top and the bottom thereof and extending inward from the lower wall of said stem substantially perpendicular to the axis of said opening effective for shielding it from a current of air entering said compartment through the passage of said stem.

4. In a bubble pipe, a bowl comprising a compartment closed at its upper end and having an outlet opening at its lower end adapted for reception of a bubble forming solution, a stem defining a passage opening into said compartment adjacent the upper end thereof, and a baffle within said compartment disposed to shield said outlet opening from a current of air entering said compartment through the passage of said stem, the outer end portion of said stem being readily flexible for constricting the passage thereof and thereby regulating air flow therethrough.

5. In a bubble pipe, a substantially cylindrical bowl formed of a plastic and separated interiorly by a readily flexible partition into two superposed compartments, the upper adapted for reception of a body of liquid and the lower having a restricted outlet opening adapted for reception of a bubble forming solution, and a tubular stem comprising two separate superposed passages, the upper constructed to provide a whistle opening into said upper compartment adjacent the bottom thereof and the lower opening into said lower compartment.

6. In a bubble pipe, a bowl comprising a substantially cylindrical compartment closed at its upper end by a flat top wall substantially normal to the axis of said compartment, the latter having an outlet opening at its lower end adapted for reception of a bubble forming solution, a stem defining a passage inclined downward and inward of and opening into said compartment adjacent the upper end thereof, and a baffle extending inward of said compartment from the lower edge of said passage substantially parallel with said top wall.
